UNITED STATES PATENT OFFICE.

JEANNE REMY, OF NEW ORLEANS, LOUISIANA.

SKIRT-MEASURE.

1,292,056.

Specification of Letters Patent. Patented Jan. 21, 1919.

Application filed February 23, 1918. Serial No. 218,849.

To all whom it may concern:

Be it known that I, JEANNE REMY, a citizen of France, residing at New Orleans, in the county of Orleans and State of Louisiana, have invented new and useful Improvements in Skirt-Measures, of which the following is a specification.

This invention relates to a measuring device which may be advantageously employed by dress makers and other persons in obtaining the length of wearing apparel, particularly skirts.

The primary object of the invention is to provide a simple and inexpensive measure of this character which is so constructed that it may not only be employed to obtain the waist and hip measure of a skirt but also may be advantageously used to obtain the proper length of the skirt at various points, so that the skirt when worn will hang evenly.

Another object of the invention is to provide slides of novel construction by means of which a plurality of adjustable measuring tapes are adjustably connected with a waist band.

A further object of the invention is to provide a measuring device with a waist band which may be quickly applied and adjusted about the waist and is so constructed that the skirt may be firmly held at the waist by the band while the wearer of the skirt employs the measuring tape to determine the length of the skirt.

With these and other objects in view the invention resides in the novel combination and arrangement of parts which will be hereinafter described and claimed.

In the drawing:

Figure 1 is a perspective view of a skirt measure constructed in accordance with the invention.

Fig. 2 is an enlarged sectional view on the line 2—2 of Fig. 1.

Fig. 3 is a view in side elevation of a portion of the waist band.

Like characters of reference denote the corresponding parts throughout the various views in the drawing.

Referring now to the drawing in detail the letter A designates a skirt measure which when constructed in accordance with the invention includes a waist band 5 formed from a strip of fabric having printed thereon inches and fractions thereof. The strip from which the band 5 is formed has formed

in one edge thereof spaced notches 6 in which may be arranged the bill of a hook 8 at one end of the strip to hold the strip in band formation as shown in Fig. 1 in the 60 drawing.

The graduated strip which is intended to be employed in obtaining the waist and hip measure of a skirt is passed through a plurality of slides which are preferably 4 in 65 number and indicated in the drawing by the numerals 9, 10, 11, and 12.

Each of the slides which are movable longitudinally of the strip comprising the waist band 5 is formed from a strip of material which is bent to form a rectangularly shaped body portion 13, one side wall of which is bent to present to the outer face of the band 5 a convexed surface 14 by means of which the slide may be held in 70 75 adjusted position upon the band.

The body 13 has formed in one end wall thereof a pair of spaced slits 15 through which passes a reduced extension 16 at one end of the strip from which the body 13 is 80 formed. The extension terminates in an elliptical shaped head 17 which is bent to overlie the slits 15 and has formed therein a longitudinally extending slot 18.

A weighted measuring tape 19 which may 85 be employed to determine the length of the skirt at a predetermined point, so that the skirt will hang evenly when worn, is passed adjacent its upper end through the slot 18 and has its upper end connected with a slide 90 20 on the tape and by means of which the tape may be lengthened or shortened.

When it is desired to employ the measure to insure a skirt being of the proper length to hang evenly when worn, the strip from 95 which the waist band is formed is adjusted about the waist. The slides 9 and 10 are now moved longitudinally of the band until they occupy a position at the front and back thereof after which, the slides 11 and 12 are adjusted on the band until they are above the hips. The tapes 19 are now adjusted by means of the slides 20 until the weights at the lower ends of the tape touch the floor. The top of the skirt may now be 100 105 adjusted to the required height above the top of the waist band 5 at various points until the bottom of the skirt is spaced an even distance from the floor at all points.

From the foregoing description taken in 110 connection with the accompanying drawing it is apparent that an inexpensive skirt

measure has been provided which is highly efficient for the purposes stated.

Having thus described my invention what is claimed as new, is:

5. 1. A skirt measure comprising a graduated waist band having a longitudinally extending row of spaced notches in one edge thereof, a hook at one end of said band and adapted to extend within said notches, and 10 a plurality of measuring tapes slidably and adjustably connected with said band.
2. A skirt measure comprising a flexible strip having a number of graduations and a plurality of spaced notches in one edge 15 thereof, a hook at one end of said strip adapted to extend within said notches, a plurality of slides through which said strip

is passed, and a weighted measuring tape adjustably connected with each of said slides.

3. In a device of the class described, a tape carrying slide formed from a strip of material bent to a rectangularly shaped slide body having an outwardly curved side wall and a pair of spaced slits in one end wall thereof, an extension at one end of said strip from which said body is formed passed through said slits, and a head at one end of said extension, bent to overlie said slits and having a longitudinally extended slot therein.

20 25 30
In testimony whereof I affix my signature.

JEANNE REMY.
